ATTORNEY

UNITED STATES PATENT OFFICE.

SARA GOLDMAN, OF SAN FRANCISCO, CALIFORNIA.

SANITARY-NAPKIN HOLDER.

1,146,245.

Specification of Letters Patent. Patented July 13, 1915.

Application filed October 12, 1914. Serial No. 866,287.

To all whom it may concern:

Be it known that I, SARA GOLDMAN, a citizen of the United States, and a resident of the city and county of San Francisco and State of California, have invented certain new and useful Improvements in Sanitary-Napkin Holders, of which the following is a specification.

This invention is an improved sanitary garment for receiving the menstrual discharge of women.

Referring to the drawings: Figure 1 is a perspective view of the garment as it appears when in position for use. Fig. 2 is a plan view of the inside of the garment. Fig. 3 is a cross sectional view of the garment holder with the parts thereof in position to permit placing of the napkin therein. Fig. 4 is a cross sectional view of the garment complete.

The garment comprises a waterproof napkin holder 1 and a napkin 2 of absorbent material, such as raw cotton, which rests within the holder and is provided with substantially flat edges 2^x. Along the respective sides of the holder are formed flaps 3 which fold over upon the side edges 2^x of the napkin and hold the napkin against lateral displacement. Fasteners, preferably snap buttons 4, are arranged on the holder at the ends of the flaps 3, which fasteners are adapted to hold the flaps in folded position upon the edges of the napkin and are adapted to engage the ends of the napkin and prevent longitudinal displacement thereof. The flaps thus folded and fastened form pockets into which the edges of the napkin may be inserted or from which said edges may be removed without unfastening the buttons 4. The flaps when remaining fastened form permanent pockets into which the edges of the napkin may be inserted edgewise.

The ends of the holder are detachably connected by means of safety pins 5 or other suitable fasteners, to the ends of elastic supporting straps 6 (which straps are maintained in proper position on a woman's

body in any suitable manner well known in the art), whereby the garment is supported in position between the woman's legs with the napkin uppermost so as to receive the woman's menstrual discharge.

The garment may be readily removed upon disengaging the fasteners 5 from the straps 6, and the napkin may be removed from the holder upon disengaging the fasteners 4 and unfolding the flaps 3. Conversely, a new napkin may be readily placed in position in the holder and held therein upon folding down the flaps 3 upon the side edges of the napkin and securing the ends of the flaps to the holder by the fasteners 4, and the garment may then be readily placed in position for use and supported in such position upon securing the ends of the holder to the straps 6 by means of the fasteners 5.

I claim:

1. A garment of the type disclosed comprising a napkin holder, a napkin, flaps along the respective sides of the holder adapted to be folded on a definite line upon the side edges of the napkin to detachably hold the napkin in the holder, fasteners for fastening the ends of the flaps beyond the napkin to the holder and means for detachably supporting the garment in position.

2. A garment of the type disclosed comprising a napkin holder, a napkin, flaps along the respective side edges of the holder for engaging the side edges of the napkin and detachably holding the napkin in the holder, snap button fasteners arranged between said holder and said flaps for fastening the ends of the flaps beyond the napkin to the holder and means for detachably supporting the garment in position.

In testimony whereof, I have hereunto set my hand, at San Francisco, California, this 7th day of October, 1914.

SARA GOLDMAN.

In presence of—

A. GOLDMAN,
ALICIA LAGAN.
